UNITED STATES PATENT OFFICE.

LEVI STEVENSON, OF LEWISTOWN, ILLINOIS.

SELF-WAITING TABLE.

SPECIFICATION forming part of Letters Patent No. 463,004, dated November 10, 1891.

Application filed February 5, 1891. Serial No. 380,358. (No model.)

To all whom it may concern:

Be it known that I, LEVI STEVENSON, a citizen of the United States, residing at Lewistown, in the county of Fulton and State of Illinois, have invented certain new and useful Improvements in Self-Waiting Tables; and I do hereby declare the following to be a full, clear, and exact description of the invention, such as will enable others skilled in the art to which it appertains to make and use the same.

My invention consists in a new and improved self-waiting table, which will be hereinafter fully described and claimed.

Referring to the accompanying drawings, Figure 1 is a top plan view of my new and improved self-waiting table. Fig. 2 is a central vertical sectional view of the same. Fig. 3 is a top plan view with the movable center of the table removed. Fig. 4 illustrates in detail one of the legs.

The same numerals of reference indicate corresponding parts in all the figures.

Referring to the several parts by their designating-numerals, 1 indicates the legs of the table, of which four are employed. The upper ends of these legs, which are formed, as shown, with the four wide faces 2 and the one narrow face 2^a, are arranged with the narrow faces 2^a outward, as shown in Fig. 3, and are connected at their upper ends by the horizontal boards or pieces 3. The upper ends of the corners 2^c of the legs which face inward are recessed to form the seats 4, on which rest and are secured the ends of two cross-pieces 5, which cross at their centers at right angles. Upon the narrow outer faces 2^a of the four legs are secured brackets 6, the upper ends of which lie flush with the upper ends of the table-legs. The outer stationary part 6 of the circular table is formed of four curved sections or segments 7, the straight ends of which meet in a close joint on the top of the table-legs on a line with the center of the said legs, the cross-pieces 5, and the outer brackets 6, these brackets thus serving to support firmly the outer part of the joints, rendering the stationary annular part of the table firm and solid. The upper edges of the horizontal pieces 3 are formed with deep recesses 8, in which are mounted the bearing-wheels 9. These wheels consist each of a grooved wheel,

in the deep groove of which a rubber ring is seated, the wheel being pivoted in a fork 10, the lower end of which is formed with a screw 10^a. The wheels are thus secured in the recessed pieces 3 by screwing the screws 10^a into the pieces 3 within the recesses 8 when the wheels 9 project up sufficiently far to receive and support the revolving center of the table.

11 indicates the circular revolving center of the table, to the center of the under side of which is secured a hard-wood block 12, having a bearing recess or hole 12^a, in which fits a pivot-pin 13, which is secured on the center 65 of the cross-pieces 5. This pivot-pin merely serves as a guide-pin to keep the center of the revolving center 11 at the center of the table. The revolving center 11 rests near its outer edge and is supported upon the rubber-tired wheels 9, and the circular edge of this part 11 is formed with an annular recess 14 on its upper side, thus forming an annular edge flange 15. The inner edge of the sections 7 is recessed at 16, forming a flange 17, 75 beneath which the edge flange of the revolving center 11 projects. This construction prevents the edge of the revolving center from rising accidentally at any point above the level of the table and makes a snug joint, 80 which prevents any vertical open space between the stationary and revolving sections of the table. It will be further seen that the annular edge flange 15 of the revolving center fitting under the overreaching annular 85 flange 17 of the stationary outer part of the table will hold the revolving central part in place at all times, so that the table can be handled at all times like an ordinary solid table in packing or shipping and in transporting it from place to place, permitting of its being turned over on its side or upside down, as the under flange 15 of the revolving center fitting under the annular flange 17 of the stationary part 7 will hold the revolving 90 center in place at all times. The center 11 is provided near its outer edge with the series of knobs 18, by means of which it can be easily and conveniently turned.

From the foregoing description, taken in connection with the accompanying drawings, the construction, operation, and advantages

of my new and improved self-waiting table will be readily understood. It will be seen that the revolving center will move with great ease and with the minimum of friction, and that the entire table is very light, strong, and durable.

Having thus described my invention, what I claim, and desire to secure by Letters Patent, is—

- 10 The combination of the legs 1, the upper ends of which are formed with four wide faces 2 and a narrow face 2^a, arranged with the narrow face 2 outward and connected at their upper ends by the horizontal pieces 3, and the corners of the legs which face inward being recessed to form the seats 4, the cross-pieces 5, having their ends resting in and secured in said seats 4, the brackets 6, se-
- 15

cured to the outer face 2^a of the four legs, the outer stationary portion of the table formed of four sections or segments 7, recessed to form a flange 17, beneath which the edge flange of the revolving center 11 projects, the knobs 18 near the outer edge of the revolving center, the horizontal pieces 3, formed with deep recesses 8, and the bearing-wheels 9, consisting each of a grooved wheel in the groove of which is seated a rubber ring, substantially as specified.

In testimony whereof I affix my signature in presence of two witnesses.

LEVI STEVENSON.
